UNITED STATES PATENT OFFICE.

ALEXANDER GODFREY, OF BRADFORD, MASSACHUSETTS.

LAST.

1,094,988.

Specification of Letters Patent. Patented Apr. 28, 1914.

Application filed July 31, 1911. Serial No. 641,666.

To all whom it may concern:

Be it known that I, ALEXANDER GODFREY, a citizen of the United States, residing at Bradford, in the county of Essex and State 5 of Massachusetts, have invented certain new and useful Improvements in Lasts, of which the following is a specification.

My invention relates to improvements in lasts which, while capable of use in any situation where it would operate in a proper manner is particularly constructed for use upon a machine in the manufacture of shoes, the object being the production of a two-part last which is capable of a swinging action 15 to shorten the last and permit the ready withdrawal of the shoe from the last.

Another object of my invention is the provision of a last which is attached to the machine in inverted or upset position, and 20 which receives the upper and which, when the work upon the upper is finished, is shortened in length to permit the withdrawal of the upper.

Another object of my invention is the provision of a last which cannot possibly become accidentally removed from its proper adjustment, but which can be instantly shortened in length and which last will be of the simplest and most durable construction 25 possible and be capable of production at a very low price.

With these objects in view, my invention consists of a last of the character and for the purpose stated embodying novel features 35 of construction and combination of parts substantially as disclosed herein.

Figure 1 represents a plan view of a last constructed in accordance with and embodying my invention. Fig. 2 represents a side 40 elevation of the complete last, partly broken away, to disclose details of construction, and Fig. 3 represents a face view looking at the inner portion of the heel member, showing particularly the blade and the automatic locking devices carried by the heel member.

My last consists of the front or toe member A, provided in its inner portion with the socket or chamber B, and with the extension C, and the heel member D, which has 50 cured centrally thereof the plate F, formed with the extension or blade G which normally lies within the socket or chamber of the toe section. The said blade is provided with the pair of oppositely inclined slots H, 55 in which sit the pair of pins or studs J, which pass through the toe section, this con-

struction providing a flexible or hinged connection between the toe and heel members and also permitting, by reason of the slots, a certain amount of movement or play 60 which results naturally in the shortening of the last when the toe section is tilted and moved toward the heel member.

Upon the flat face K of the heel member is pivoted the locking plate L which, by reason 65 of the slot M and the stud N fitting in said slot, permits the plate a slight movement, and the plate is held in normally locked position by means of the flat spring O which bears against said plate, said spring being 70 restrained from improper movement by means of the stop P and the locking plate when the last is open or distended, engaging the keeper Q, carried by the toe member.

In use the last is secured upon a suitable 75 jack or support by means of the socket R in the heel member, and when it is desired to shorten the last, contact is made, with the lug S on the locking plate, which releases the locking plate from the keeper and permits the toe section or member to be tilted 80 and moved inward, shortening the last and permitting the withdrawal of the finished upper and the application of another upper, it being understood that the tilting of the 85 toe section immediately locks it in the extended position.

The last is particularly adapted for use upon machines used in the manufacture of shoes where a sectional or two-part last 90 capable of a swinging action to shorten the last and permit the ready removal of the shoe therefrom is especially needed, and it is the function of the present invention to provide a contact means upon the locking 95 plate of the last which the contact device of the machine may strike against to shorten the last. This is an important feature of the invention, the specific arrangement of the locking plate and contact lug 100 serving to insure a firm and positive contact to effect the releasing of the sections and permit their swinging action.

It will be understood that while my last is particularly adapted for use in connection with a machine in the manufacture of boots and shoes, the last can be used for the purpose of exhibiting shoes, or for keeping the upper of the shoe in proper shape and appearance, and the advantages of my last 110 will be readily understood by all conversant or skilled in the art.

It will be noted that the heel portion of my last is provided with an inner inclined wall and that the toe portion is formed with an opposite practically vertical wall, and that the connection between the heel and toe members or portions permits the closing of the portions into a small space to permit the removal of the shoe from the last, and that I provide a novel means for locking the sections which is automatically released by the machine.

I claim:

1. The last herein described, consisting of a heel section having an upwardly and backwardly inclined front wall, a plate secured in said heel section and formed with a forwardly projecting extension and provided with a pair of oppositely inclined slots, a toe section formed with a socket to receive the horizontally extending portion of the plate carried by the heel section, a pair of pins carried by the toe section and passing through the oppositely inclined slots of the plate, said slots being arranged to permit the heel section to be moved bodily forward toward the toe section, said toe section being formed with an inner practically perpendicular wall, the parts so arranged that the heel section may be brought forward to

bring the inclined wall thereof substantially 30 parallel with the perpendicular wall of the toe section to shorten the last, and means for securing the last when extended and for releasing the sections when necessary.

2. A last comprising a heel section having an upwardly and backwardly inclined front wall, a toe section having a horizontal upper face, means connecting such sections and permitting relative movement therebetween, and means for securing the sections 40 in extended position and for releasing them when necessary, consisting of a keeper on the horizontal upper face of the toe section, a pivoted cam shaped latch mounted on the inclined wall of the heel section, means for 45 guiding said cam-shaped latch, a spring for holding the latch in proper position, and a stud projecting from said keeper to receive contact for releasing the keeper and permitting the heel section to move forward 50 to shorten the last.

In testimony whereof I affix my signature in presence of two witnesses.

ALEXANDER GODFREY.

Witnesses:

MILDRED F. SHEEHAN,
ETHEL MITCHELL HALE.
